UNITED STATES PATENT OFFICE

144,062

DESIGN FOR A BRACELET OR SIMILAR ARTICLE

Cressent J. Mann, Chicago, Ill., assignor to Mario Tanzi, Chicago, Ill.

Application August 27, 1945, Serial No. 121,654

Term of patent 3½ years

(Cl. D45—4)

To all whom it may concern:

Be it known that I, Cressent J. Mann, a citizen of the United States and a resident of Chicago, county of Cook, and State of Illinois, have invented a new, original, and ornamental Design for a Bracelet or Similar Article, of which the following is a specification, reference being had to the accompanying drawing, forming part thereof.

In the drawing:

Fig. 1 is a front elevational view of a bracelet or similar article, showing my design.

Fig. 2 is a side elevational view taken from the left edge thereof.

Fig. 3 is a top plan view of the bracelet shown in Fig. 1.

Fig. 4 is a flat development view of the bracelet shown in Fig 1.

I claim:

The ornamental design for a bracelet or similar article, substantially as shown.

CRESSENT J. MANN.
